UNITED STATES PATENT OFFICE

ROSWELL HUNT LYON, OF HARRISBURG, PENNSYLVANIA

DESIGN FOR A BAG

Application filed July 17, 1931. Serial No. 40,583. Term of patent 14 years.

To all whom it may concern:

Be it known that I, ROSWELL HUNT LYON, a citizen of the United States, residing at 225 South 13th Street, Harrisburg, in the county of Dauphin and State of Pennsylvania, have invented a new, original, and ornamental Design for a Bag, of which the following is a specification, reference being had to the accompanying drawings, forming part thereof.

a side view, of a bag, showing my new design.

The view shown in Figure 1 also appears on the back of the bag, and the view shown in Figure 2 appears on both sides of the bag. The bag is substantially rectangular in cross-section.

I claim:

The ornamental design for a bag, as shown and described.

ROSWELL HUNT LYON.
